RADIO ANTENNA LOCATED IN OUTER EDGE
OF RUNNING BOARD

Harvey D. Geyer, Dayton, Ohio, assignor to General Motors Corporation, Detroit, Mich., a corporation of Delaware

Application November 9, 1935, Serial No. 49,002

4 Claims. (Cl. 250—33)

This invention relates to an automobile running board having a radio antenna element supported and insulated by a resilient rubber portion of the running board.

5 An object of this invention is to provide an automotive radio antenna located adjacent the extreme outer edge of the running board whereby to avoid the shielding effect of other metal parts of the vehicle and to render the antenna 10 less susceptible to interference from other electrical circuits and spark impulses of the automobile.

Another object is to provide an antenna which is completely protected against water, wind, ice, 15 snow, etc., contacting same when in use, and which is very substantially protected against physical damage thereto by striking foreign objects or raised projections in the roadway. Still another object is to provide such an antenna 20 that is very simple and economical to manufacture and install upon the automotive vehicle and which does not interfere with any other parts or accessories on the vehicle or use any space which can be normally used in any other way.

25 Further objects and advantages of the present invention will be apparent from the following description, reference being had to the accompanying drawing wherein a preferred embodiment of the present invention is clearly shown.

30 In the drawing:

Fig. 1 is an isometric view of the running boards, front fenders, radio set and the antenna connections thereto shown in their relative positions.

35 Fig. 2 is a plan view of the front end portion of the left running board and shows one way of connecting the antenna wire to the metal shielded lead-in wire.

Fig. 3 is a section on line 3—3 of Fig. 1 or 40 Fig. 2 and shows the location of the antenna wire relative to other metal portions of the running board.

Similar reference characters refer to similar parts throughout the several views.

45 In the form shown in Fig. 3, 1 designates the sheet metal plate, preferably steel, of the running board proper which extends downwardly at its outer margin and is preferably flared outwardly, as at 2, for purposes hereinafter described, 3 is a reinforcing or stiffening metal channel extending longitudinally adjacent the outer margin of the board, 4 is the molded soft rubber step covering which is preferably vulcanized directly upon the steel plate 1. 5 is the 50 outer marginal protective guard or bead and is 55

molded of resilient rubber preferably integral with the step covering 4 and bonded by vulcanization to the flared metal portion 2 whereby it is substantially supported against such great downward deflection as might sooner or later 5 tear it or shear it off.

Within the extreme outer portion 6 of the resilient rubber bead 5 there is embedded a preferably flat flexible strip 10 of metal, preferably copper, which extends substantially the full 10 length of the board and which constitutes the antenna wire for picking up the radio waves. It is to be noted that this antenna wire 10 is spaced laterally outward beyond any metal portion of the running board and thus avoids to the maximum extent the radio shielding effect of all other metal parts of the running board and other metal portions of the vehicle. The further the wire 10 can be spaced laterally outwardly from the other metal parts of the vehicle the more 15 efficient it will serve to pick up the radio signals and the less interference it will experience from the other electric circuits of the ignition system of the vehicle. Such a spacing of two inches from the metal part 2 has been found to give 20 very good results. The rubber bead 5 may be easily made more than two inches wide without 25 making it excessively heavy or costly and still provide sufficient strength for the purposes described.

30 The antenna wire 10 may be conveniently molded in situ just barely within the outer edge of the rubber portion, or the rubber portion may be molded with a slit 11 therein, within which the flat wire 10 is inserted after vulcanization 35 of the rubber. Or, if desired, the rubber may be molded solid and the slit 11 cut therein afterwards for the reception of the flat wire 10. In all cases the antenna wire 10 will be substantially completely protected from being wet by 40 water, ice, or snow thrown up by the auto wheels and also will be fully protected from physical damage by striking foreign objects. It will be noted that the flat wire 10 is quite flexible and hence will readily flex with the rubber bead 5 45 when that is distorted for any reason but it will not be damaged by such distortion.

Antenna wires 10 are preferably used in both the right and left running boards and are connected together by a cross wire 12, their rear ends 50 9 terminating near the rear ends of the boards and not connected to anything. The cross wire 12 is connected by lead-in wire 13 to the antenna terminal of the receiving set 14. Wires 12 and 13 are preferably shielded by a metal armor or shield 55

15 which is grounded to the chassis frame by ground connection 16 to which the set 14 is also grounded. Thus wires 12 and 13 will be shielded against picking up noises from the electric systems of the vehicle and hence the only effective antenna wires will be the suitably and efficiently located flat wires 10 which are not shielded by any metal.

Fig. 2 illustrates how the outer ends of the metal shield 15 may be suitably secured to the rubber boss 20 molded integral with the running board by means of a small metal clamp ring 21 so that no water may enter this joint. The ends of the flat antenna wire 10 and the cross wire 12 15 may be simply twisted together or otherwise suitably connected and the connection insulated from the metal shield 15 by rubber tape or other simple means.

While the embodiment of the present invention as herein disclosed, constitutes a preferred form, it is to be understood that other forms might be adopted, all coming within the scope of the claims which follow.

What is claimed is as follows:

25 1. In combination, a running board for an automotive vehicle comprising an outer marginal reinforcing structural member of metal, a longitudinal resilient rubber marginal guard supported by said structural member and projecting laterally outwardly materially beyond all structural metal members of the board, and a radio antenna element embedded within said resilient rubber guard adjacent its outer marginal edge and insulated and supported thereby in such a position laterally outwardly spaced beyond all structural metal portions of the board as to substantially avoid harmful radio shielding effects of said metal portions of the board.

2. In combination, a running board for an automotive vehicle comprising an outer marginal reinforcing structural member of metal, a longitudinal resilient rubber marginal guard supported by said structural member and projecting laterally outwardly materially beyond all structural metal members of the board, and a flexible metal antenna element embedded within and supported by the resilient rubber guard adjacent its outer marginal edge, said antenna element being readily distortable in situ with the surrounding resilient rubber to accommodate the movement of the rubber when distorted by outside forces.

3. In combination, a running board for an automotive vehicle comprising an outer marginal reinforcing structural member of metal, a longitudinal resilient rubber marginal guard supported by said structural member and projecting laterally outwardly materially beyond all structural metal members of the board, said rubber guard having a marginal longitudinal slot therein adjacent its outer edge, and a radio antenna element inserted within said slot and held flexibly retained in place by said resilient rubber.

4. In combination, a running board for an automotive vehicle comprising an outer marginal reinforcing structural member of metal, a resilient rubber guard materially overhanging the outer margin of said metal structural member and supported thereby by a surface bond thereto, and a longitudinally extending antenna element embedded in said resilient rubber guard relatively close to the outside edge thereof whereby said antenna element is substantially laterally removed from the radio shielding effect of said metal structural member.

HARVEY D. GEYER.
